[57] CLAIM

The ornamental design for a combined vapor and oil collection unit for attachment to a diesel engine breathing tube, as shown.

DESCRIPTION

FIG. 1 is a perspective view of a combined vapor and oil collection unit for attachment to a diesel engine breathing tube showing my new design;

FIG. 2 is a front elevational view thereof;

FIG. 3 is a rear elevational view thereof;

FIG. 4 is a top-plan view thereof; and

FIG. 5 is a bottom plan view thereof.

FIG. 1

FIG. 2

FIG. 3

FIG. 4

FIG. 5
